UNITED STATES PATENT OFFICE.

FREDERICK E. LEAVITT, OF ST. PAUL, MINNESOTA.

SURGICAL INSTRUMENT.

SPECIFICATION forming part of Letters Patent No. 769,483, dated September 6, 1904.

Application filed November 23, 1903. Serial No. 182,244. (No model.)

To all whom it may concern:

Be it known that I, FREDERICK E. LEAVITT, a citizen of the United States of America, and a resident of St. Paul, in the county of Ramsey 5 and State of Minnesota, have invented certain new and useful Improvements in Surgical Instruments, of which the following is a specification.

My invention relates to an improved surgical instrument commonly known as a "uterine dilator."

The object of my invention is to provide an instrument for obstetric and gynecological purposes which while simple in construction 15 and effective in use may also be easily and quickly taken apart and rendered aseptic.

To these ends my invention consists of a fulcrum and a plurality of separable dilating-levers, which are applied to said fulcrum 20 when used.

My invention further consists of the features of construction and combination of parts hereinafter more particularly described and claimed.

In the accompanying drawings, forming part of this specification, Figure 1 is a side view of my improved surgical instrument. Fig. 2 is a detail view of Fig. 1, showing part of the fulcrum-piece in section. Fig. 3 is a 25 sectional view of Fig. 1, showing one end of the fulcrum-piece. Fig. 4 is a view of the other end of the fulcrum-piece. Fig. 5 is a detail view of the ends of a pair of the levers, and Figs. 6, 7, 8, and 9 are detail views of various forms of the ends used on the dilating-levers.

In the drawings let A represent the fulcrum-piece and B the dilating-levers. The fulcrum-piece, as shown, consists of a shank 2, having 30 disks 3 and 4 on its ends, which form fulcrums for the dilating-levers. These fulcrum-disks are recessed at 5 to receive the dilating-levers. The recesses are equally spaced apart on the periphery of each disk and are formed with knife-bearing edges 6, on which the angles of the notches 7 between the ends of the dilating-levers are placed, as shown in Fig. 2. The dilating-levers, as shown, are four in number and similar in construction, except as herein-

after stated, and are adapted to rest on one of the fulcrums when used. If only a small amount of dilation is desired, the levers are applied to the small fulcrum 3 and if a greater amount is desired they are applied to the large fulcrum. In either case the power ends of 55 the levers extend back over the shank of the fulcrum-piece 2, as shown in Fig. 1.

In use the fulcrum is held in the hand and one of the disks applied to the notches in the levers, as shown in Fig. 1, after their ends 60 have been inserted for use. A rubber band 8 is then passed around the ends of the levers, which extend over the shank 2. The power ends of the levers are grasped by the hand when it is desired to supplement the force exerted by the rubber band or additional rubber bands are passed around the levers. The ends of the levers and fulcrum may be changed 65 and the instrument used either for obstetric or gynecological purposes. One set of ends 70 of the levers is designed for obstetric and the other for gynecological use.

By the use of the means above described a constant and effective force is applied by means of the levers.

As shown in Fig. 5, the end 9 of one lever is made smaller in diameter than the corresponding ends of the other three, and the convex side 10 of one of the other corresponding ends is grooved at 11 in such a way as to 75 permit the smaller-sized lever to pass within and alongside said groove when the levers are first applied and used.

In Figs. 6, 7, 8, and 9 modified forms of ends of the levers are shown, and as it will 80 be obvious to those skilled in the art to which this invention relates that the ends of the levers may be suitably designed for the various uses for which this instrument is adapted without departing from the spirit of this invention I do not wish to confine myself to the specific construction specified. It is also obvious that while I have shown and described 85 four levers three or any suitable number may be used, also that some other means may be 90 used in place of the rubber band for applying power to the levers.

Having described my invention, what I

claim as new, and desire to protect by Letters Patent, is—

1. An instrument of the class set forth, consisting of a fulcrum, a plurality of reversible, dilating-levers, and means for detachably fastening said levers on said fulcrum.

2. An instrument of the class set forth, consisting of a plurality of reversible, dilating-levers, a fulcrum-piece having different-sized heads, and means for detachably fastening said levers on either head, for the purposes specified.

3. An instrument of the class set forth, consisting of a plurality of reversible, dilating-levers, a fulcrum-piece having different-sized heads, means for detachably pivoting said levers on either of said heads, and actuating means for said levers.

4. An instrument of the class set forth, consisting of reversible, dilating-levers, and a fulcrum-piece having an enlarged end which is provided with recesses in which said levers are adapted to be detachably pivoted.

5. An instrument of the class set forth, consisting of a fulcrum-piece having enlarged ends which are provided with recesses, and a plurality of dilating-levers, notched to pivot on said ends, in said recesses.

6. An instrument of the class set forth, consisting of a fulcrum-piece having enlarged ends, a plurality of dilating-levers, and means by which said levers are removably and pivotally attached to said ends.

7. An instrument of the class set forth, con-

sisting of a fulcrum-piece having notched disks of different diameters on its ends, a plurality of dilating-levers having means for engaging the notches in either one or the other of said disks, and mechanical means for applying power to said levers.

8. An instrument of the class set forth, consisting of a fulcrum-piece having a shank, a pair of disks of different diameters on the ends of said shank and provided with recesses in their peripheries, dilating-levers, notches in said levers adapted to engage the recesses in either one or the other of said disks, and an elastic band around the power ends of said levers.

9. An instrument of the class set forth, consisting of a fulcrum-piece having fulcrum-disks of different diameters on its ends, a plurality of dilating-levers having their ends formed with convex surfaces, and means for engaging said levers with a disk, one of said levers being smaller at the end than the others, while another lever is grooved to permit the end of said smaller lever to pass within and alongside said groove when said levers are first inserted for use.

In testimony whereof I have signed my name to this specification in the presence of two subscribing witnesses.

FREDERICK E. LEAVITT.
